UNITED STATES PATENT OFFICE.

ALEXANDER E. CAMERON, OF PROVIDENCE, RHODE ISLAND, ASSIGNOR TO NARRAGANSETT ELECTRIC LIGHTING COMPANY, OF PROVIDENCE, RHODE ISLAND, A CORPORATION OF RHODE ISLAND.

BOILER-PRESSURE REGULATOR.

Application filed January 14, 1922. Serial No. 529,328.

This invention relates to a system of boiler pressure regulation and has for one of its objects the provision of means for maintaining a practically constant steam pressure in the boilers through control of the several factors governing combustion within the furnace.

Another object of the invention is the provision, in a steam generating installation, of a system of boiler pressure regulation, including a draft regulator responsive to pressure conditions in the draft duct leading to the furnace, in combination with a steam pressure controlled regulator having means associated therewith for regulating a duct damper and the fuel supply to the furnace.

Another object of the invention is the provision of a device operated by hydraulic pressure and responsive to draft pressure in the draft duct, said device functioning to actuate means by which the speed of the blower, in a forced draft steam generating system, or a damper in the draft duct of a constant draft system, is controlled.

Another object of the invention is the provision of a hydraulic pressure distributing valve actuated by a steam pressure responsive regulator, which valve admits hydraulic pressure to a governing device associated with the furnace and by which the duct damper and fuel supply to the heating means are controlled.

With the above and other objects in view, my invention consists in the improved draft pressure, steam pressure, damper and fuel oil controlling apparatus illustrated in the accompanying drawings, described in the following specification, and particularly claimed and in such variations and modifications thereof as will be obvious to those skilled in the art to which my invention relates.

In the drawings accompanying and forming a part of this specification and wherein the preferred embodiment of my invention is illustrated:

Figure 1 is a diagrammatic view of a steam generating installation which my steam pressure regulating system is incorporated.

The other views show details of the several novel units which are combined in my

invention, in which Figure 2 is a view partly in cross section of the pressure bell. 55

Figure 3 is a view, partly in section, showing the master pilot valve and one of the governing devices with indicated connections between the two, said pilot valve and governing device being drawn to different 60 scales;

Figure 4 is a diagrammatic view of a steam blower which is used as an alternative construction to the motor blower shown in Figure 1, and Figure 5 is a view in cross section showing details of the "Mason's" 65 regulator.

Referring now in particular to the system which is embodied in the layout shown in Figure 1, the furnace A is provided with 70 boilers B and with heating means which in this case is represented by the oil burners C.

The burner supply pipes D are each connected in two ways to the main fuel supply pipe E, by a reducing valve E' which is not 75 controlled and supplies a quantity of fuel just sufficient to support low fire, and a diaphragm-controlled valve F which is capable of communicating to the burners the full capacity of the fuel supply-pipe, at a 80 predetermined fixed pressure.

The furnace is supplied with air from a draft blower G located in the air duct H which leads into a main air duct I, the air being carried from the latter to the furnace 85 through the duct J. A number of furnaces may be supplied with air from the main air duct I. The blower damper K controls the supply of air to the main air duct and the damper L controls the draft supply to the 90 individual furnaces.

In controlling the steam pressure in a system such as has been here outlined in which a number of furnaces are fed by the same source of air pressure it is essential that 95 the regulation shall include the maintenance of constant forced draft pressure in the main air duct as well as control of the draft and fuel conditions in the individual furnace. To this end two regulating devices 100 are provided, the one shown at the right hand of Figure 1, and designated by the letter M being of the type known as the "Mason's" regulator, which comprises a diaphragm, not shown in the drawing, beneath 105 which steam from the boilers is admitted, in

this case through the pipe N which communicates with the steam main O. The diaphragm rises more or less, according to the steam pressure, lifting the weighted arm P, which is connected to a pivotally mounted lever Q operating a plunger valve R. The "Mason's" regulator has in it a plunger S which is connected with a reciprocating rod T by means of which any desired regulating mechanism may be actuated. A source of water pressure such as a city main U is in communication with the under side of the plunger S when the plunger valve R is in depressed position, and the under side of said plunger is in communication with a drain V at atmospheric pressure, when the plunger valve R is raised. The plunger rod T is connected to the master pilot valve W, the detailed construction of which will be presently described and which distributes hydraulic pressure from a city main to the governing device X which regulates by means of the cable Y the individual duct damper J and the diaphragm fuel valve F. If desired the "Mason's" regulator may also control a stack damper Z by means of the cable a'. The "Mason's" regulator per se, forms no part of my invention, and is of well known construction.

The hydraulic regulator b', shown at the lower left hand side of Figure 1, is similar to the "Mason's" regulator, except that the steam actuated diaphragm and weighted arm P are done away with and in their stead the pivotally mounted lever c' is provided, which functions similarly to the lever Q to operate a valve similar to the valve R said lever being actuated by a pressure bell d' and the latter being in communication with the forced draft supply duct H by means of a pipe e' responsive to the air pressure within said duct. From the top of the hydraulic regulator b' extends the reciprocating rod f' which is connected with the damper K. In this case the fan G is driven by an electric motor but, if desired, the alternative form of construction shown in Figure 4 may be used which comprises a steam turbine fan, the steam supply valve g' of which will be connected to the top of the hydraulic regulator and the damper K being dispensed with.

Referring in detail to the construction of the pressure bell d', this apparatus as shown in Fig. 2, preferably consists of a metal bell 1, suspended by a metal hanger 2, the latter being fastened to the bell by means of the machine screws 3. The hanger may be provided with a metal top 4 held in place by two machine screws 5 into which is seated a V-block 6.

A suitable lever 7, running through a sleeve 8 and held in place by a set screw 9, is provided with a fork 10 fastened at one end by means of the rivet 11. Into the fork 10

is set a knife edge 12 upon which the V-block 6 is supported. The other end of the lever 7 is provided with a sliding weight 13 the position of which may be fixed at any point along the lever 7 between the sleeve 8 and the free end thereof by means of a thumb screw 14. The weight 13 serves to counter-balance the bell 1.

The lever 7 is shown as being supported by means of a V-block 15 set into the sleeve 8 and resting on a knife edge 16 supported by a standard 17.

The bell 1 is suspended over a base 18 to which the standard 17 is fastened by means of a machine screw 19.

In the embodiment shown in the drawings, the base 18 is provided with two annular channels 20 and 21 formed by four walls 22, 23, 24 and 25 rising perpendicularly from the base 18. These channels 20 and 21 are filled to a suitable depth with mercury into which the ring shaped flanges 26 and 27 of the bell 1 are allowed to dip, the level of the mercury being kept the same in both channels by means of an equalizing tube 28.

An air pipe e' is screwed into the base 18 and communicates at one end with the chamber 30 which is enclosed between the bell 1 and the base 18. Since the chamber 30 is sealed from the atmosphere by the mercury, any increase in pressure within the chamber 30 will cause the bell 1 to rise, the adjustable weight 13 assisting in this operation. Likewise, a decrease in pressure in the chamber 30 below that of the atmosphere will cause the bell 1 to fall.

The V-blocks 6 and 15 rest upon the knife edges 12 and 16 rather than vice versa in order to prevent the accumulation of dirt or foreign matter in the V-block slots which might interfere with the practically frictionless operation of the apparatus. For the same reason the bell may be provided with a dust proof sheet metal casing 31. A stem 32 passes through the center of the bell 1 and is secured in any suitable manner to the hanger 2, as by the check nut 33. This stem is used to transmit the rising and falling motion of the bell 1 to the lever c' which is pivotally secured to the hydraulic regulating device b'. Passing down through a hole in the base 18 the stem 32 is pivotally connected to said lever c' by means of a fork 35. This lever also is provided with an adjustable weight 36 so that the bell 1 may be "loaded" to operate at any desired pressure. This also has the advantage of steadyng the bell 1 and causes all the pressure exerted to bear directly upon the knife edge 6.

As shown in Figure 1 on the left hand side, the lever c' is connected intermediate its fulcrum 37 and its point of connection with the stem of the plunger valve of the modified

"Mason's" regulator or hydraulic regulator b'.

The pilot valve W is secured above the "Mason's" regulator M, shown on right hand 5 side of Figure 1, and operatively connected to the plunger rod T thereof, said valve being shown in detail in Fig. 3 and consisting of a cylinder 46 to which are sweated or otherwise secured five metal rings 47, 48, 10 49, 50 and 51. The four of the rings first mentioned are cored out so that annular ports 52, 53, 54 and 55 are formed. These rings 47, 48, 49 and 50 are provided respectively with the pipes 56, 57, 58 and 59. 15 The pipes 57 and 59 serve to conduct water to and from the governing device X and the other pipes 58 and 56 serve as supply and exhaust pipes respectively, the former being connected to the city water supply and 20 the latter to a drain. The top ring 51 is blank and serves to hold the head 60 in place thereby closing the end of the cylinder 46, the head being secured by suitable means such as by cap screws 61. The ring 47 is 25 secured to the bottom of the cylinder 46 and although serving as an exhaust port for the water affords also a means for fastening the supporting plate or disk 62 to the cylinder 46. 30 The bottom head 63 is fastened to the disk 62 by means such as the cap screws 64 and 65, and is provided with a stuffing box. It closes the bottom end of the cylinder 46 and prevents the leakage of exhaust water 35 around the plunger rod T which passes through it and connects with the "Mason's" regulator M. Water from the several ports 52, 53, 54 and 55 is admitted to the cylinder by a number of small holes 67 drilled 40 into the cylinder wall offering a passage-way for the water from the ports to the interior of the cylinder. Within the cylinder 46 is a balanced piston 68 one end 69 of which is removably secured in order that it may be removed 45 to renew the cup leather packings 70 and 71 and to remove the washers 72 and 73 which hold the packing 70 and 71 flat against the piston ends. The balanced piston 68 is of proper length to afford a free passage 50 from supply port 54 to the port 55 when at the upper limit of its range of travel and also to connect the ports 54 and 53 at the lower limit of its range of travel.

The piston 68 is also hollow through the center as shown at 66, a free passage being thus allowed for the exhaust of water from the port 55 to the exhaust port 52. A free passage for exhaust between the ports 53 and 52 is also left when the piston 68 is at the 60 top of its cylinder.

The plunger rod T is fastened to the piston 68 by means such as a pin 74 passing through the lower end of the piston 68 and said plunger rod. The wrist joint thus formed 65 permits the piston 68 to center itself within

the cylinder 46 and prevents it from binding.

Four rods, two of which are shown at 75 and 76 support the pilot valve over the "Mason's" regulator. The supporting rods 75 and 76 are preferably reduced at each 70 end and threaded, the upper ends of these rods passing through holes in the disk 62 where they are made fast by nuts 77 and 78. A disc similar to the disc 62 may be fastened to the top of the "Mason's" regulator by cap 75 screws and furnishes means for fastening the lower ends of the rods 75 and 76 to said regulator. Of course any means whatsoever may be substituted in place of the means shown for positioning the pilot valve in operative relation to the Mason's-regulator. 80

The pipes 57 and 59 communicate respectively with ports 85 and 86 at the top and bottom of the cylinder 87 which forms part of the governing device X. This cylinder is provided with suitable means, such as top and bottom brackets 88 and 89, by means of which the governing device may be secured to the wall or other suitable support. 85

To the bottom bracket 89 is secured a head 90 closing the bottom end of the cylinder 87 and held in place by suitable means such as cap screws. The top bracket 88 is also provided with a head 91 which serves to close 90 the top of the cylinder 87, the head being held in place in the same manner as is the bottom head 90. The top head 91 is constructed with a stuffing box 93 through which passes a stem 94. 95

To the lower end of the stem 94 and within the cylinder 87 is attached a piston 95 provided with two cup leather packings 96 and 97 both of which are held against the piston 95 by means of two washers 98 and 99. The piston 95, concave packings 96 and 97 and washers 98 and 99 are held in place by a nut 100 and a shoulder 101 turned on the stem 94. The cup side of each packing faces outwardly from the piston in order to prevent leakage on either side thereof. 100

Passing through the heads 90 and 91 and extending upwardly are two guide rods 102 and 103 of suitable length. These rods are secured rigidly to the lower head and its associated parts in any suitable manner, being shown as clampably held to the lower bracket and head, between the nuts 104 and 105 and shoulders formed at the base of reduced portions of said rods. 105

Where guide rods 102 and 103 pass through the top head 91, the head is slotted as shown at 106 so that it may be raised to give access to the upper end of the piston without dismantling any other part of the apparatus. Two sliding guides 107 and 108 are fastened to the stem 94 by means of taper pins 109 and 110 and slide along the guide rods 102 and 103 as the stem 94 moves up and down. 115

Two fixed guides 111 and 112 are fastened 120

to the guide rods 102 and 103 by means of taper pins 113 and 114, the stem 94 sliding through the guide 111 which acts as a stop, as will presently be shown. The guide 112 is semi-circular and is fastened to the upper ends of the guide rods 102 and 103 and keeps the guide rods equally spaced. On account of its shape the guide 112 does not interfere with the axial position of the upper end of the stem 94 and the cable attached thereto. All of these guides keep the guide rods 102 and 103 and the stem 94 in alignment and prevent the piston 95 from binding.

15 The stem 94 is threaded from its upper end where the guide 108 is fastened and is provided with two knurled adjustment discs 116 and 117 so that travel of the piston 95 may be limited by engagement of said 20 adjustment disks with the stop formed by the guide 111 as the stem 94 moves up and down. A suitable connection 118 is screwed on the upper end of the stem 94 above the guide 108 by means of which the cable Y 25 may be attached, the latter leading to the damper L shown in Figure 1. Another cable a', as hereinbefore pointed out, may lead from the connection 118 to the stack damper Z.

30 For the successful operation of the steam regulating system embodied in this invention it is essential that the draft supplied to the main air duct I be constant in order that the opening of the branch duct damper L 35 or the stack damper Z, in case the latter is used, shall have the same effect at all times upon the draft conditions within the furnace.

40 This constancy of draft pressure supplied to the main air duct I is accomplished by means of the bell d' the movements of which are responsive to changes of draft pressure in the conduit H which are communicated to the bell by means of the conduit e'. The bell actuates the modified "Mason's" regulator or hydraulic regulator b' which controls the opening and closing of the damper K. As hereinbefore stated, if a steam fan be used instead of the constant speed blower G, the modified "Mason's" regulator b' will 45 actuate the valve g' shown in Figure 4, which controls the speed of the steam driven fan, a damper between the fan and main duct being then unnecessary.

50 The movement of the dampers L or Z or both which govern the draft conditions in the individual furnaces and also the actuation of the diaphragm valve F is accomplished by hydraulic pressure acting through the governing device X and governed by the pilot valve W which is servient to the "Mason's" regulator M. City water under pressure of, say, 60 pounds, enters the conduit U 55 above the plunger of the valve R and enters beneath the plunger of the "Mason's" reg-

ulator raising the plunger rod T which causes the piston 68 in the master pilot valve W to ascend to the top of its cylinder 46, thus placing the pipe 58 in communication with the pipe 59 which leads to the bottom 70 of the cylinder of the governing device. The pipe 58 being connected to the city water main at the substantially constant pressure of say 60 pounds, this pressure is communicated through the pipe 59 to the lower 75 end of the plunger 95 of the governing device raising the latter until the disk 116 strikes the stop 111. This limits the upward stroke of the plunger 95 and consequently limits the degree of opening of the dampers 80 L or Z which are attached to a cable or cables secured to the fitting 118 at the top of the plunger stem 94. This upward position of the plunger of the governing device is the low fire position of the dampers 85 L and Z and when in this position a pipe 92 which communicates with the upper part of the cylinder of the governing device and is designed to convey hydraulic pressure to the diaphragm valve F is shut off from the pressure side of the plunger 95. Therefore, the diaphragm valve is closed and fuel oil is supplied to the burners through the pressure reducing valve E' at which pressure the oil 90 is admitted to the burners in a quantity merely sufficient for maintaining a normal steam pressure.

Should the steam pressure in the boilers decrease, it acts upon the "Mason's" regulator M so as to move the lever Q to a low 100 position in which the hydraulic pressure is relieved from the lower surface of the plungers of the "Mason's" regulator, the water finding its way freely out by means of the drain conduit V which is in communication with the atmosphere. This permits the plunger rod T to descend, pulling the piston 68 down, thereby allowing the water to flow from the inlet pipe 58 into the pipe 57 which is in communication with the upper end of the cylinder of the governing device. This causes the plunger 95 of said device to descend putting the cables leading to the dampers L or Z into tension and moving said dampers to open position. The downward movement of the plunger 95 continues until the disk 117 strikes the upper side of the stop 111. This disk, like the disk 116, is adjustable on the plunger stem 94 and determines the limit of opening of said dampers. When the plunger 95 has descended to the lower limit of its stroke the hydraulic pressure in the upper end of the cylinder of the governing device immediately builds up to a maximum pressure which communicates through pipe 92 to the diaphragm F. This valve, as has been stated, opens at a pressure slightly less than the constant pressure in the city water main or other source of hydraulic pressure; therefore, when the hy- 110 115 120 125 130

draulic pressure is communicated to it through the pipe 92, it will open, permitting a flow of oil at an increased pressure to the burners, thus raising the fires, and thereby increasing the generation of steam until the steam pressure reaches its normal point, at which time the operation of the apparatus is reversed and the fire again drops back to its normal condition. In the meantime the exhaust water from the lower end of the cylinder 46 of the governing device W has drained through the pipe 59 and passage 66 of the piston 68 out through the pipe 56 to a sewer or drain.

Having described my invention what I claim as new and desire to secure by Letters Patent, is:—

1. In a steam generating system comprising a furnace and boiler, a main draft conduit adapted to supply said furnace, means for creating draft pressure within said conduit, means for controlling the supply of draft to said furnace, means responsive to conditions of draft pressure within said conduit between said draft creating means and controlling means for governing said draft creating means to maintain constant pressure in said conduit, and means responsive to conditions of steam pressure within said boiler for governing said first named draft controlling means.

2. In a steam generating system comprising a furnace and boiler, a main draft conduit adapted to supply said furnace, means for creating draft pressure within said conduit, means for controlling the supply of draft to said furnace, fuel supply means for said furnace, means responsive to conditions of draft pressure within said conduit between said draft creating means and controlling means, for governing said draft creating means to maintain constant pressure within said conduit, and means responsive to conditions of steam pressure within said boiler for governing said first named draft controlling means and said fuel supply means.

3. In a steam generating system comprising a furnace and boiler, a main draft conduit adapted to supply said furnace, means for creating draft pressure within said conduit, means for controlling the supply of draft to said furnace, a hydraulic regulator responsive to conditions of draft pressure within said conduit between said draft creating means and controlling means for governing said draft creating means to maintain constant pressure in said conduit, and a second hydraulic regulator responsive to conditions of steam pressure within said boiler for governing said first named draft controlling means.

4. In a steam generating system comprising a furnace and boiler, a main draft conduit adapted to supply said furnace, means

for creating draft pressure within said conduit, means for controlling the supply of draft to said furnace, a pressure bell responsive to conditions of draft pressure within said conduit and in communication with said conduit between said draft creating means and said controlling means, a lever moved by the rise and fall of said bell, a plunger responsive to movements of said lever for governing said draft creating means to maintain constant pressure in said conduit and means responsive to conditions of steam pressure within said boiler for governing said first named draft controlling means.

5. In a steam generating system comprising a furnace and boiler, a main draft conduit adapted to supply said furnace, an air blower for creating draft pressure within said conduit, a branch conduit leading from said main conduit to said furnace, means in said branch conduit for controlling the supply of draft to said furnace, means responsive to conditions of draft pressure within said main conduit between said draft creating means and controlling means for governing said blower to maintain constant pressure in said main conduit, and means responsive to conditions of steam pressure within said boiler for governing said draft controlling means.

6. In a steam generating system comprising a furnace and boiler, a draft conduit adapted to supply said furnace, means in said conduit for controlling the supply of draft to said furnace, a fuel valve for said furnace, fluid pressure operating means for actuating said fuel valve, a governing device for controlling the movements of said draft control means and for governing said fuel valve, including a cylinder, a piston in said cylinder operatively connected to said draft control means, one side of said cylinder being in communication with the actuating means for said fuel valve, means for admitting fluid under substantially constant pressure to the opposite sides of said cylinder to actuate said draft control means and supply said fuel valve actuating means, said piston yielding to said fluid pressure to prevent the transmission of an operative degree of fluid pressure to said fuel valve actuating means until said piston reaches the limit of its range of movement.

7. In a steam generating system comprising a furnace and boiler, a draft conduit adapted to supply said furnace, means in said conduit for controlling the supply of draft to said furnace, a fuel valve for said furnace, fluid pressure operating means for actuating said fuel valve, a governing device for controlling the movements of said draft control means and for governing said fuel valve, including a cylinder, a piston in said cylinder operatively connected to said

- draft control means, one side of said cylinder being in communication with the actuating means for said fuel valve, means for admitting fluid under substantially constant pressure to the opposite sides of said cylinder to actuate said draft control means and supply said fuel valve actuating means, said piston yielding to said fluid pressure to prevent the transmission of an operative degree of fluid pressure to said fuel valve actuating means until said piston reaches the limit of its range of movement and adjustable means for varying the extent of said range of movement.
- 10 8. In a steam generating system comprising a boiler, a furnace, and combustion control mechanisms associated with said furnace, a device for operating said combustion control mechanisms, said device comprising a cylinder, a piston mounted for reciprocation within said cylinder and operatively associated with one of said control mechanisms, a valve for operating said device including a cylinder, a pressure supply conduit leading from a source of constant hydraulic pressure communicating with said valve cylinder at a point intermediate its ends, a pair of conduits communicating with said valve cylinder at points respectively above and below said pressure supply conduit and connected one to each end of the cylinder of said device, a drain conduit connected to said valve cylinder adjacent the lower end thereof, a piston in said valve cylinder having an annular channel bridging said pressure supply conduit and, alternately, either the upper or
- lower of said conduits leading to said device, said lower conduit being in communication with said drain conduit when said piston is in a position in which the annular piston chamber connects the upper conduit leading to said device to the fluid pressure supply conduit, said piston having a passage therethrough placing the upper conduit leading to said device in communication with the drain conduit when said upper conduit is not bridged by said annular piston chamber, and means responsive to variations of steam pressure in the boiler for actuating said piston.
- 15 9. In a steam generating system comprising a furnace and boiler, a draft control device and a pressure actuated fuel supply valve for said furnace, a governing device comprising a cylinder, a piston reciprocable within said cylinder, the ends of said cylinder above and below said piston being alternately communicable with a source of constant hydraulic pressure, a conduit leading from one end of said cylinder to the fluid pressure actuated means in said fuel supply valve, guides supported by said cylinder, a threaded stem for said piston travelling through said guides, threaded disks adjustably mounted on said stem, on opposite sides of one of said guides, the latter acting as a stop for said disks to limit the range of movement of said piston, said stem being connected to said draft control means.
- 20 In testimony whereof I have hereunto set my hand.
